UNITED STATES PATENT OFFICE

2,285,079

ELECTROMAGNETIC SOUND-REPRODUCING DEVICE

Günther Behre, Berlin, Germany, assignor to C. Lorenz Aktiengesellschaft, Berlin-Tempelhof, Germany, a company

Application March 29, 1940, Serial No. 326,601
In Germany March 7, 1939

3 Claims. (Cl. 179—100.2)

The invention relates to sound-reproducing devices of the kind having a wire, tape or plate as record carrier on which the sound to be reproduced is magnetically impressed.

The hitherto known methods of sound reproduction fail to produce tones of the same perfection throughout the entire voice frequency range. When only one magnet pole cooperates with the record carrier low frequencies are well reproduced free from any distortion, whereas the reproduction of high frequencies is distorted. With two magnet poles used for reproduction high frequencies are better reproduced than low frequencies which are distorted.

In order to avoid these disadvantages the invention provides for reproducing the low frequencies mainly by means of one pole and the high frequencies mainly by two poles. To such end in a preferred embodiment of the invention a filter circuit including a condenser and a choke coil is employed whereby no switching-over from the one to the two pole arrangement be necessary.

Three embodiments are diagrammatically represented in Figs. 1, 2 and 3 of the drawing.

1 and 2 denote magnet poles which belong to coils 3, 4 of a so-called talking head. These coils are interconnected in series. Between the poles 1, 2 the record carrier 5 extends, which may be a wire, a tape or a plate. In the lead to coil 3 a condenser 6 is included. Coil 3 and condenser 6 are bridged over by a choke coil 7.

Owing to this arrangement the coil 3 will be ineffective in the case of low frequencies, since condenser 6 acts as a high resistance with respect to them. As regards high frequencies however, the coil 7 in its turn acts as a resistance, thus causing the current to pass through both coils 3, 4.

It will be seen that a resistance may be arranged in lieu of coil 7.

The invention is not restricted to the device here shown. For instance, the reproduction may be made by means of two talking heads one of which is unipolar in action while the other is bipolar. Furthermore, two talking heads may be arranged to operate each in bipolar fashion, one of them being adapted to reproduce high fre-

quencies while the other is suitable for the reproduction of low frequencies. In such structures the talking heads themselves constitute the filter circuit.

5 According to the embodiment shown in Fig. 2 one reproducing head is unipolar and consequently favors the low frequencies, whereas the other is bipolar and responds better to the high frequencies. In Fig. 2, numeral 1' represents the 10 sound carrier. 2', 3' are the poles and 4', 5' the windings of the bipolar reproducing head, whereas the unipolar reproducing head consists of pole 6' with winding 7'. The windings of the two 15 reproducing heads are connected in parallel.

15 Another embodiment of the invention is shown in Fig. 3, using two bipolar reproducing heads for the pick-up. Since as stated above, a bipolar reproducing head reproduces best the high 20 frequencies, an air-gap between pole and sound carrier is provided for in one of the reproducing heads, whereby the low frequencies are favored 25 in the pick-up. Fig. 3 represents the sound carrier 1'', the poles 2'', 3'' with winding 4'', 5'', of one of the bipolar reproducing heads and poles 6'', 7'' with windings 8'', 9'' of the other bipolar reproducing head. The two reproducing heads are connected in parallel.

What is claimed is:

1. In a sound reproducing device for magnetic 30 sound carriers, a pick-up comprising at least two opposed poles, and means including a filter circuit for rendering part of said pick-up effective to reproduce only low frequencies.

2. In a sound reproducing device for magnetic 35 sound carriers, a pick-up comprising two opposed poles, coils for said poles, a connection between one of the terminals of said coils, a condenser having one plate connected with the other terminal of one coil, and an impedance between 40 the first mentioned connection and the other plate of said condenser.

3. In a sound reproducing device for magnetic 45 sound carriers, a pick-up comprising two opposed poles and a single pole, coils for said two poles connected in series, and a coil for said single pole bridged across said coils.

GÜNTHER BEHRE.
